UNITED STATES PATENT OFFICE.

BLASDEL SHAPLEIGH, OF ST. LOUIS, MISSOURI.

FASTENING TOOL-HANDLES.

1,199,117.

Specification of Letters Patent. Patented Sept. 26, 1916.

Application filed November 16, 1914. Serial No. 872,304.

To all whom it may concern:

Be it known that I, BLASDEL SHAPLEIGH, a citizen of the United States, and a resident of the city of St. Louis and State of Missouri, have invented a new and useful Improvement in Fastening Tool-Handles, of which the following is a specification.

My invention relates to methods of and devices for fastening handles to tool-heads having eyes therein, such as axes, hammers and the like.

The heads of some tools like axes and hammers, are made with eyes in which wooden handles are inserted. In this type of tool 15 the handle is commonly held in place in the tool-head by a wedge which is driven into the end of the handle to expand said handle and bind it tightly in the eye of the tool-head. In this type of handle fastening, the wedge 20 is quite liable to work loose and allow the handle to slip out of the tool-head.

My invention has for its objects to make a wedge fastening of the character above described in which the wedge cannot work 25 loose; and to attain certain advantages which will be more fully set forth herein-after.

Generally stated, the invention consists in fastening tool handles by means of a metal 30 wedge which is driven into the end of the handle and permanently held in place by a connection welded to the tool-head.

In the accompanying drawing which forms part of this specification and in which 35 like reference characters refer to like parts in the several views, Figure 1 is a side elevation of an ax showing a handle fastening embodying the invention applied thereto, the ax-head being partly in section; Fig. 2 is an 40 end elevation of the ax showing the handle fastening applied thereto; Fig. 3 is a longitudinal section through the handle on the line 3—3 in Fig. 1; Fig. 4 is a perspective view of the wedge which constitutes part of 45 the handle fastening; and Fig. 5 is a perspective view of the retaining member which constitutes part of the handle fastening.

Referring to the accompanying drawing, a fastening device embodying the invention 50 is shown applied to an ax having a head 1 in which there is the usual eye 2. The handle 3 is inserted in the eye 2 and is held in place by a wedge 4 which is driven into the end of said handle lengthwise of the eye 55 2. In the outer or exposed end of the wedge 4 is a notch 5.

The retaining member 6 or auxiliary wedge (see Fig. 5) is a wedge-shaped block having two prongs or legs 7. The retaining member 6 has integral therewith two thin strips or ears 8 which project outwardly at the outer or thicker end of said retaining member. The retaining member 6 is also driven into the end of the handle 3 crosswise of the eye 2, and substantially at right angles to the wedge 4. The two legs 7 of the retaining member 6 straddle the wedge 4, and the middle portion of said retaining member 6 fits into the notch 5 of said wedge 4. The retaining member 6 is driven into 70 the handle 3 until the ears 8 of said retaining member touch the ax-head 1; and these ears 8 are welded to said ax-head, preferably electrically, by the process generally known as spot welding. The outer ends of the wedge 75 4 and the retaining member 6 are preferably flush with the outer edge of the ax-head 1, and any humps or protuberances on the ax-head which may result from the welding are removed by an emery wheel or other means. 80

In the construction shown and hereinbefore described, the retaining member 6 prevents the wedge 4 from working out of the handle 3. The retaining member 6 is permanently secured to the ax-head 1 and cannot work loose. In some cases the wedge 85 itself may be welded to the ax-head 1, and such a construction comes within the scope of the invention. The use of a separate retaining member is preferable because it does not hold the wedge 4 in a fixed position relative to the ax-head 1, so that if the handle should start to pull out, the wedge may move with it and keep the handle tight until it is pulled completely out. 90

While for the purpose of illustration, the invention has been shown as applied to a handle fastening for axes, the same construction can be used for fastening a handle to the head of any tool in which the handle is inserted and secured in an eye in said head. The particular construction shown and hereinbefore described may be considerably changed without departing from the invention, and I do not wish to be restricted 100 to the details of this construction nor to the method of applying it. 95

What I claim as my invention is:—

1. A handle fastening for tool-heads having eyes with handles arranged therein, said 110 fastening comprising a wedge driven into the handle and movable with relation

thereto, and a retaining member secured to the head of said tool across the eye thereof outside of said wedge, said retaining member preventing movement of the wedge outward through the eye while permitting driving of the handle farther through the eye or driving of the wedge farther into the handle.

2. A tool head having a tapered eye, a handle in said eye, an expanding wedge in said handle movable inward with relation thereto toward the small end of said eye, and a locking wedge secured to the head preventing movement of said expanding wedge outward, said wedges permitting driving of the handle farther through the eye and driving of the expanding wedge farther into the handle.

3. The process of fastening a handle in the eye of a tool head which comprises inserting the handle in the desired position in the eye, driving a wedge through the open end of the eye into the end of the handle in the eye, arranging a fastening member crosswise thereof to hold said wedge from working loose and securing said fastening member to the tool head.

4. The process of fastening a handle in the eye of a tool head which comprises inserting the handle in the desired position in the eye, driving an expanding wedge through the open end of the eye into the end of the handle in the eye, driving a fastening wedge through the open end of the eye into the handle against the expanding wedge and crosswise thereof and securing said fastening wedge to the tool head.

5. A tool head having a tapered eye open at both ends, a handle in said eye, an expanding wedge in said handle movable therewith and movable with relation thereto in the direction of the small end of the eye, and a narrow retaining member secured to the head of said tool across the eye outside of said wedge to prevent its withdrawal, said retaining member permitting movement of the expanding wedge toward the small end of the eye.

Signed at St. Louis, Missouri, this 13th day of November, 1914.

BLASDEL SHAPLEIGH.
